UNITED STATES PATENT OFFICE

2,354,953

CARD GAME

Andrew S. Kinney, Redwood Falls, Minn.

Application November 16, 1942, Serial No. 465,743

1 Claim. (Cl. 273—152)

This invention relates to a card game, one of the objects being to provide a new and novel means whereby children can be instructed in the fundamentals of the calendar year, namely, the months, weeks, days of the week, changes of season, A. M. and P. M. of the day, hours of the day and minutes. While the game is especially useful for educational purposes it can also be employed entertainingly by adults.

A further object is to provide a deck of cards on which are displayed clock faces indicating different times of the day and night, there being supplemental indications on the cards for designating the days of the week, the months of the year, the number of days in the months, and changes of season.

A further object is to provide a deck made up of two suits, one constituting a day suit and the other constituting a night suit while in addition thereto there are supplemental cards known as "Sunday" cards and a joker or "Leap Year" card.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

In the accompanying drawings the preferred form of the invention has been shown.

In said drawings

Figure 1 is a face view of the week-day cards of the night suit.

Figure 2 is a face view of the week-day cards of the day suit.

Figure 3 is a face view of the Sunday cards of the night suit.

Figure 4 is a face view of the Sunday cards of the day suit.

Figure 5 is a face view of the joker or "Leap Year" card.

As will be noted by reference to the drawings, the deck of cards is made up of a night suit and a day suit together with a joker. The night suit can be printed in black while the day suit can be printed in red although other colors could be employed. The night suit is divided into twelve week-day cards and two Sunday cards and the day suit is similarly divided.

In addition to the cards of the two suits, there is provided a joker or "Leap Year" card illustrated in Fig. 5. It is preferred to make the top half of this card to correspond in color to that

of one suit while the bottom half corresponds in color to that of the other suit, the top part in Fig. 5 belonging to the night suit while the lower part in said figure belongs to the day suit.

5 It will be noted that each card of each suit is designated by a day of the week. For example the day cards of each suit are divided into two groups, each group being designated by the days of the week from Monday to Saturday inclusive. The cards of the night suit, however, bear the further designation of the hours from 1 to 12 P. M., the first Monday card being designated "1 P. M.", the first Tuesday card being designated "2 P. M." and so on throughout the twelve cards the last Saturday one of which is designated "12 P. M." In the day suit, however, shown in Fig. 2, the first Monday card of the suit is designated "1 A. M."; the Tuesday card is designated "2 A. M." and so on throughout the series of twelve cards the last or Saturday card of which is designated "12 A. M."

Each card of each suit has the same designation at both of its ends, the designations being oppositely disposed. Each card of each suit is also provided with two large clock faces indicated at 1, the clock faces being oppositely disposed and indicating the time of day designated in the title portion of the card. For example the first Monday card of the night suit in Fig. 1 indicates one o'clock while the second or Tuesday card indicates two o'clock. This is continued throughout the suit of twelve cards the last of which indicates twelve o'clock.

Between the clock faces of the night suit is the printed notification "Begins at noon." This notification appears twice at this point, one being disposed oppositely to the other so as to be legible when the card is positioned with either end uppermost.

40 Between the clock faces on the day cards shown in Fig. 2 are printed the notifications "Begins at midnight." This notification is also duplicated, one being disposed oppositely to the other so that the information is legible when the card is positioned with either end uppermost.

In addition to the two large clock faces appearing on each card, smaller clock faces corresponding therewith are located in diagonally opposed corners as indicated at 2, these small clock faces designating the same time as the larger ones. Adjacent to each of the smaller clock faces is also printed an abbreviation of the day of the week designated adjacent to the large clock faces.

55 The twelve week-day cards of each suit are further designated by the month of the year. In

other words the Monday card of each suit carries at opposite sides thereof the name "January" and adjacent thereto there is displayed information concerning the month, namely, "1st month—31 days." Each Tuesday card is further designated by the name of the next month "February" adjacent to which is displayed the information "2nd month—28 days." This arrangement is continued throughout the extent of the week-day cards of each suit.

Attention is directed to the fact that while the week-day cards of one suit indicate the same hour of the day as does the corresponding card of the other suit, said suits differ in that the cards of one suit bear a further designation "P. M." while the day cards of the other suit bear the designation "A. M." Likewise the cards of the night suit bear the designation "Begins at noon" while the cards of the day suit bear the designation "Begins at midnight."

In addition to the week-day cards of the two suits, there are provided two Sunday cards for each suit. The Sunday cards of the night suit are shown in Fig. 3. The clock faces on one of these cards indicate twelve o'clock while the clock faces on the other card indicate six o'clock. The twelve o'clock card is designated "12 P. M." adjacent to the word "Sunday" and carries the further designations "September 23rd autumn begins" and "12 hours in P. M." The second card of the night suit bears the designations "6 P. M." "December 21st winter begins" and "52 weeks in a year."

The Sunday cards in the day suit differ from those of the night suit in that the designations thereon in addition to the word "Sunday" are "12 A. M." One of these Sunday cards in Fig. 4 bears the further designation "March 20th spring begins" and "60 minutes in an hour" while the other Sunday cards bear the designation "June 21st summer begins" and "12 hours in A. M."

In Fig. 5 there is shown a joker or "Leap Year" card. This is not always used but is employed in the game whenever some predetermined penalty is to be imposed upon the holder thereof or the holder is to be given a certain advantage to be determined by the rules of the game. This joker or "Leap Year" card, shown in Fig. 5, has its clock faces indicating eleven o'clock and one end thereof bears the designation "P. M." while the other end bears the designation "A. M." Further designations appearing on this card are "February 29th comes every four years" and "Year of ladies' choice."

Different games can be played by the use of these cards the primary purpose being to give instructions in time and in the days, weeks, months and seasons of the year.

The following are the rules of one game which can be played with these cards:

After the cards have been well shuffled four cards are dealt from the deck to each of the players. From two to four players can engage in the game. Following dealing of the cards the remainder of the deck is turned face-down and the player to the left of the dealer begins by drawing top card of the deck and lays their play in the center of the table—all Sunday cards must be laid first and as soon as they are drawn. Books begin with Sunday 6 & 12 and ends with Saturday 6 & 12—each book is one week and makes four weeks in the deck.

Example.—Monday 7 plays on Sunday 6 up to Saturday 12 and Monday 1 plays on Sunday 12 up to Saturday 6 and all must be of the same

suit. Each player must draw before playing and play as many cards as they choose. As the play is made the day and hour must be called—when a player is through playing or cannot play, he calls the word "Time."

Errors in plays.—Any player making a mistake in the time of laying cards, must draw a card from the deck. If the deck is drawn, he draws from the player's hand that calls the error.

The player that rids his hand of cards before the last card on the books is played wins the game.

In the foregoing game the joker need not be used although it could be employed either as a penalty or as an advantage.

Another game utilizing the joker or "Leap Year" card but omitting the six o'clock Sunday cards can be played by shuffling the cards well and dealing them to the players. The highest "Day" card deals. Monday (one, low) and Saturday (twelve, high). Deal 4 cards, one around to the left. Turn remainder of deck face-down.

The play.—The two "Sunday" cards must be played as soon as drawn and placed in the middle of the table. Player to the left of dealer draws the top card. Books are built on "Sunday" cards starting from Monday (one) to Saturday (twelve) of the same suit. The only card a player can pass the play on is the "Leap Year" card which is wild and can be played on any day or suit at any time after Sunday. The other suit cards must not be passed on but may be played one or more as the player chooses. For example: If three cards in the hand can be played and one is played, this is not an error—for the player has not passed without playing and may force the opponent to play on books that the player has a high card on. This may help the player win the game.

Errors.—The player that makes a mistake in laying cards, draws a card from the player who calls it.

Scoring.—The player that rids his hand of cards before the last card on the books is played, wins the game.

It is possible also to play a game of "Solitaire" with the cards, the "Leap Year" or joker card being eliminated. In this game the Sunday cards must be laid up first and books are built up in rotation of the dial and must be of the same suit. For example: Monday 1 plays on Sunday 12 and Monday 7 plays on Sunday 6 through to Saturday 6 and 12 making four weeks in all.

Hold the deck face-down and deal three cards at a time through the deck, always lay face up. Play as many cards as possible from the top card down. Deal the deck over as long as you can play.

When the player can't play on books by dealing three cards through the deck, then he starts dealing two cards at a time. Never shuffle the deck until the game is over. This game can be beat on an average of two or three times out of ten.

As before stated the joker card could be used in all of the games if desired by modifications of the rules as stated.

What is claimed is:

A card game including two suits of cards bearing the indicia "A. M." and "P. M." respectively, each suit including twelve cards designated by the respective names of the months of the year, said "month" cards of each suit being divided into six pairs, the cards of each pair being fur-

ther designated by the six days of the week, the cards of each group of a suit being provided with opposed duplicate clock faces thereon each indicating an hour of the day differing from that indicated on the other card of the same group, there being two "Sunday" cards included in each suit, the "Sunday" cards of one group bearing

the indicia "A. M." and the name of one month of the year and the "Sunday" cards of the other group bearing the indicia "P. M." and the name of another month, the "Sunday" cards of each group having clock faces indicating different hours of the day.
